BEVERAGE DISPENSING MACHINE

Erdick Nelson, Chicago, Ill., assignor to Square
Manufacturing Company, a corporation of
Illinois

Application August 4, 1949, Serial No. 4,294

Term of patent 14 years

(Cl. D52—3)

To all whom it may concern:

Be it known that I, Erdick Nelson, a citizen of the United States, residing at Chicago, in the county of Cook and State of Illinois, have invented a new, original, and ornamental Design for a Beverage Dispensing Machine, of which the following is a specification, reference being had to the accompanying drawing, forming a part thereof.

Figure 1 is a front elevational view of a beverage dispensing machine showing my new design;

Figure 2 is a side elevational view of the machine looking from the left of Figure 1; and

Figure 3 is a top plan view of the machine.

I claim:

The ornamental design for a beverage dispensing machine, as shown.

ERDICK NELSON.
